FOUNTAIN PEN WITH CARTRIDGE BARREL

Fred D. Woods, Glencoe, Ill., assignor to Auto-point Company, Chicago, Ill., a corporation of Illinois

Application April 15, 1947, Serial No. 741,461

1 Claim. (Cl. 120—45.4)

1

The present invention relates to fountain pens and more particularly to a novel cartridge barrel for a fountain pen that is removable and replaceable when the ink with which the barrel is initially supplied becomes exhausted.

The novel invention comprehends a unique and simplified fountain pen comprising a nib end assembly and a removable and replaceable barrel assembly providing an ink reservoir and a closure which permits limited flow of the ink when the pen is assembled.

Among the objects of the present invention is to provide a novel cartridge type barrel forming a closed ink receptacle which remains sealed until it is secured or assembled upon the nib end of a fountain pen. At such time, access is had to the ink supply in the barrel and thereupon the ink flows to the nib.

It is a further object of this invention to provide a novel closure or valve member for the barrel which is automatically opened when the barrel and nib end are mounted in assembled relation, and which functions in such manner as to automatically control the flow of ink from the barrel.

The invention further comprehends a novel and simplified construction of a removable and replaceable part for a fountain pen providing an ink reservoir for holding a substantial quantity of a standard liquid type ink, and provided with a novel control for regulating the flow of ink to the pen nib and thereby prevent flooding.

Another object of the present invention is to provide a novel ink cartridge sold as a replacement for the barrel of a pen and each cartridge providing a quantity of ink that will supply all requirements for a relatively long period of time. It is contemplated to form the barrel of a plastic material that is inexpensive and that may be discarded when empty and replaced by a new barrel or cartridge.

A further object of the present invention is to provide a combined barrel and ink container sold as a separate unit assembly for replacement on a fountain pen, and the provision of a novel closure therefor so constructed and arranged as to be automatically opened for access to and discharge of the ink only when the barrel is in assembled relation and the pen is ready for use.

Further objects are to provide a construction of maximum efficiency, economy and ease of assembly, control and operation, and such further objects, advantages and capabilities as will later more fully appear and are inherently possessed thereby.

2

The invention further resides in the construction, combination and arrangement of parts illustrated in the accompanying drawing, and while there is shown therein a preferred embodiment it is to be understood that the same is susceptible of modification and change and comprehends other details, arrangements of parts, features and constructions without departing from the spirit of the invention.

10 In the drawing:

Figure 1 is a view in vertical cross-section through a fountain pen constructed in accordance with the present invention.

15 Fig. 2 is a view similar to Fig. 1 but with the pen rotated through 90° from the position in the preceding figure.

20 Fig. 3 is a fragmentary view of the combined ink reservoir and barrel unit, part in vertical cross-section and part in side elevation, and showing the position of the closure and the vent or discharge port when in closed relation.

Fig. 4 is a view in horizontal cross-section taken in a plane represented by the line 4—4 of Fig. 1.

25 Referring more particularly to the embodiment

shown in the drawing and selected to illustrate the novel invention, the fountain pen therein shown includes a combined cartridge and barrel that is removable and replaceable when the ink supply is exhausted. It comprises a barrel 1 which may be of any desired outer contour and with its interior 2 unobstructed to form a substantially large reservoir for ink A. It is provided with a closure or valve consisting of a tubular or sleeve-like member 3 open at its lower end 4 and closed at its upper end 5, and provided adjacent its open end with a port or valve opening 6.

30 This closure is press-fitted into the bore of a collar 7 preferably formed separately of but having one end rigidly secured in the open end 8 of the barrel in any suitable manner, such as by an adhesive, plastic cement or the like, and having its outer or lower end 9 extending beyond the open end of the barrel and externally threaded for connection with the internally threaded portion 10 in the nib end cap or hood 11 of a fountain pen.

35 The nib end, hood or cap 11 is provided with a longitudinal bore for receiving a feed tube or sleeve 12, which in turn is adapted to receive a feed bar 13 and a pen nib 14. The feed bar 13 is press-fitted into the feed tube or sleeve 12 with the lower end 15 extending beyond the lower end 16 of the tube and the upper end 17 thereof 40 projecting beyond the upper end 18 of the tube,

and retained in this operative position when assembled.

The arcuate or concaved under surface of the pen nib conforms to the contour of the end 15 of the feed bar and is retained thereon by having the end 19 of the nib press-fitted into the enlarged bore in the lower end 16 of the tube or sleeve 12 and with the end of the nib abutting the shoulder 20 thereat. To permit passage or flow of ink B from the member 3 to the pen nib 14, the upper surface of the feed bar is provided with a longitudinal slot 21.

The amount of ink A that may be initially supplied by such a replacement barrel unit is considerable, although the quantity of ink that is made available to or which flows to the writing point or pen nib is limited by the quantity B available in the closure or member 3.

The feed bar 13 is preferably of rubber or rubber-like composition, while the remaining parts, except for the pen nib which will be of suitable metal, are preferably formed of a suitable plastic material and may be injection molded. Furthermore, by reason of the present novel and simplified construction, the nib 14, feed bar 13 and feed tube 12 are so constructed, designed and arranged as to be in and maintain their proper, predetermined alignment and assembly.

As the combined barrel and ink cartridge is made removable and replaceable when the ink supply in the barrel is exhausted, it will be appreciated that all that is necessary to remove the same is to unthread this barrel 1 and its associated collar 7 and closure or member 3 and to replace this unit with a similar unit which is filled with ink at the factory and sold as a replacement. As shown in Fig. 3, the closure 3 being press-fitted into the collar 7, has its opening or discharge port 6 disposed wholly within the confines of the collar and is thereby covered or closed so as to prevent leakage of ink from the reservoir to the hollow interior of the closure 3. However, when the barrel and cartridge are assembled upon the nib end, hood or cap 11 in the position shown in Figs. 1 and 2, the sleeve 14 carrying the feed bar is automatically aligned with the tubular closure 3 so that as the barrel and hood or cap are threaded into abutting relation, the feed bar 13 enters the hollow interior of the closure and the upper end 18 of the feed tube or sleeve 12 abuts against the lower end 4 of the tubular closure 3 and forces the latter upwardly or inwardly into the barrel to the position wherein the port or valve opening 6 leaves the collar 7 and is uncovered, in which position it permits ink to flow from the reservoir or interior of the barrel, through this port and into the tubular member 3, and thence along the slotted feed bar 13 to the pen nib 14. Air entrapped in the hollow interior of this enclosed tubular member 3 limits the quantity of ink permitted to flow thereinto to such an

amount as to prevent flooding of the ink to the pen nib.

From the above description and the disclosure in the drawing, it will be apparent that the present invention comprehends a novel fountain pen assembly of relatively inexpensive and simplified construction in which the barrel forms an ink receptacle or cartridge that has a large ink capacity, and when the supply is exhausted may be readily removed and quickly and cheaply replaced by another. Although the usual protecting cap for covering the nib when the pen is not in use is not shown, it is to be understood that such a cap may be employed with the present novel form of fountain pen.

Having thus disclosed the invention, I claim:

In a fountain pen having a nib assembly provided with a feed tube and a feed bar therein projecting beyond the end of the tube, a removable and replaceable barrel assembly containing a relatively large ink supply, said barrel assembly including a collar rigidly affixed to the open end of the barrel and having a part extending beyond the end of the barrel and adapted to be detachably connected to a nib assembly, and a tubular member having an outer open end press-fitted inwardly of the end of said extended part of the collar and an inner end closed and projecting into the barrel to provide in one position a closure sealing the contents of the barrel and in another position receiving a limited quantity of ink from the barrel, said tubular member being provided with a port in its tubular wall which is covered and thereby closed by the collar when the barrel is sealed against leakage but is adapted to be uncovered and opened upon contact with a feed tube part through said end of said extended part of the collar and consequent lengthwise movement of the tubular member relative to the collar and inwardly of the barrel whereby said tubular member receives a limited quantity of ink from the barrel and supplies this ink to a feed tube and feed bar.

FRED D. WOODS.
